US00D949039S

(12) United States Design Patent (10) Patent No.: US D949,039 S
(45) Date of Patent: * Apr. 19, 2022

(54) BAND

(71) Applicant: Apple Inc., Cupertino, CA (US)

(72) Inventors: Jody Akana, San Francisco, CA (US); Molly Anderson, San Francisco, CA (US); Bartley K. Andre, Palo Alto, CA (US); Shota Aoyagi, San Francisco, CA (US); Anthony Michael Ashcroft, San Francisco, CA (US); Marine C. Bataille, San Francisco, CA (US); Jeremy Bataillou, San Francisco, CA (US); Markus Diebel, San Francisco, CA (US); M. Evans Hankey, San Francisco, CA (US); Julian Hoenig, San Francisco, CA (US); Richard P. Howarth, San Francisco, CA (US); Jonathan P. Ive, San Francisco, CA (US); Julian Jaede, San Francisco, CA (US); Duncan Robert Kerr, San Francisco, CA (US); Marc A Newson, London (GB); Peter Russell-Clarke, San Francisco, CA (US); Benjamin Andrew Shaffer, San Jose, CA (US); Joe Sung-Ho Tan, San Francisco, CA (US); Clement Tissandier, San Francisco, CA (US); Eugene Antony Whang, San Francisco, CA (US); Rico Zörkendorfer, San Francisco, CA (US)

(73) Assignee: Apple Inc., Cupertino, CA (US)

() Term: 15 Years

(21) Appl. No.: 29/746,615

(22) Filed: Aug. 14, 2020

(51) LOC (13) Cl. 11-01

(52) U.S. Cl.

USPC D11/3

(58) Field of Classification Search

USPC D11/1-3; D10/30, 32, 38, 70; D14/344; D2/627, 635, 636, 638

(57) CLAIM

The ornamental design for a band, as shown and described.

DESCRIPTION

FIG. 1 is a bottom front perspective view of a band showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof, showing the band in an environment in which it may be used.

The broken lines in FIG. 9 represent environmental subject matter that forms no part of the claimed design.

1 Claim, 5 Drawing Sheets
